UNITED STATES PATENT OFFICE.

GEORGE HENRY HEMINGWAY, OF COVENTRY, ENGLAND.

INTERNAL-COMBUSTION TURBINE-ENGINE.

1,331,766.

Specification of Letters Patent. Patented Feb. 24, 1920.

Application filed April 18, 1919. Serial No. 291,016.

To all whom it may concern:

Be it known that I, GEORGE HENRY HEMINGWAY, a subject of the Kingdom of Great Britain, residing at Styvechale avenue, Coventry, in the county of Warwick, England, have invented certain new and useful Improvements in or Relating to Internal-Combustion Turbine-Engines, of which the following is a specification.

10 This invention relates to internal combustion turbine engines, and consists of the combination with a turbine of an initial rotary compressor.

The improvements have for their main 15 object the initial induction of the gases through the rotary compressor, which rotary compressor may or may not be combined with a super-compressor which may be arranged intermediately between the initial rotary compressor and the turbine.

20 The object of the super-compressor is to obtain increased compression of the gaseous mixture after initial compression through the rotary compressor and prior to ignition, 25 the improvements also embodying in combination with the rotary type of initial compressor, means for shutting off the charge, which charge is then subjected to the additional or super-compression prior to its ignition 30 and explosive operation on the turbine, the whole arrangement, including the rotary compressor, super-compressor and turbine preferably comprising a single unit.

In order that this invention may be clearly 35 understood and readily carried into practice, reference may be had to the appended explanatory two sheets of drawings, upon which:—

Figure 1 is a part sectional and part elevational plan of one embodiment of the invention.

Fig. 2 is a part sectional and part elevational plan illustrating another embodiment of the invention.

45 In an embodiment of this invention the rotary compressor *a* for effecting initial compression is arranged adjacent to the one end of the main shaft *b*, the turbine *c* being arranged at or adjacent to the other end of the main shaft *b*. Two oppositely positioned ducts or passages *d* are provided for the passage of the mixture from the rotary compressor *a* to the turbine *b*. The rotary compressor *a* at each duct is provided at its 55 inner end with a revolving disk *a* having

ports *a* which permit the gaseous mixture to flow into the ducts between the compressor *a* and the turbine *c* at given periods while the super-compressors *e* and the sliding valves for shutting off the charge are 60 arranged between the rotary compressor *a* and the turbine *b* to be operated by the main shaft *b* in opposite directions and in relation to the respective passages.

Behind each revolving disk above mentioned on the inside of the compressor or the side adjacent to the super-compressor, a spring ring *d* is arranged to make contact with the disk *a* and prevent any back pressure or escape of gas.

70 Each super-compressor *e* comprises a piston *e* which is adapted to enter a part *d* of the passage, which part is cylindrically formed to receive the slide valve *e*, the said piston being operated through the medium 75 of a connecting rod *e* by an eccentric *e* on the main shaft. A slide valve *e* in the form of a sleeve around the piston is also operated through the medium of a rod or rods *e* by eccentrics *e* on the main shaft *b*.

70 The sleeve *e* forming the slide valve is provided with ports *e*, *e*, the one *e* of which is adapted to shut off that part of the passage through which the mixture passes from the rotary compressor *a*. This cuts 85 off the gases from the rotary compressor *a*, in addition to the disk *a* having ports from the rotary compressor. The action of the sliding valve *e* and piston *e* is so timed that the slide valve *e* first closes the port *e* to the passage *d* on that side of the piston adjacent to the rotary compressor *a*, after which the advance of the piston *e* in the cylindrical part *d* of the sliding valve *e* effects a super-compression of the gases in 95 that part of the passage *d* between the super-compressor *e* and the turbine *c*.

The ignition plug is arranged at *f* in that part of the passage *d* adjacent to the entrance of the turbine *c*, the passage at this 100 point being enlarged to form an explosion chamber. The entrance between the chamber and the turbine is provided with a fixed grille or nozzle plate *d* comprised of a series of inclined blades which direct the gases 105 formed by the explosion against the blades *e* which are radially arranged in ports in the rotating part of the turbine *c*, such radially arranged blades being preferably laterally inclined. In addition, spring rings 110

d^4 are fitted at the entrance to the turbine to prevent any escape of the compressed gases previous to ignition.

The turbine c preferably consists of a series of radially arranged blades c^3 , c^5 . The first set of blades fixed into the turbine drum are so arranged as to be exposed to the explosive gases during the time of the firing only; the other portion of this first or outer disk c^2 being solid, and therefore sealing up the explosive chamber during the period of compression. Other turbine blades c^4 are mounted on a drum c^4 on the main shaft b so as to rotate between a series of similar blades c^5 which are secured to the inner circumference of the case of the turbine. The blades are of approximately crescent shaped cross section, the concave face of those fixed being in a reverse position to those which are rotated, while the ends of the blades are secured respectively to the rotating drum c^4 and inner circumference of the casing by a series of pairs of rings c^6 , between each alternate pair of which a dovetailed annular channel is formed, in which the ends of the blades which are of a dovetailed shape are fitted, suitable dovetail spacing plugs being provided between the ends of the blades, and each pair of rings riveted together to prevent disassembling the whole being secured and retained in position by adjustable screw pins c^7 in fixed rings c^8 , the ends of which screw pins impinge against the outer of the pairs of rings c^6 , thus enabling the whole of the rings to be forced tightly together. The rings c^8 are prevented from sliding back by shouldering against split spring rings which spring into grooves formed into the rotating drum and casing respectively.

The rotary compressor a may be of any suitable type, such for instance as that type which embodies a series of rotating impellers which are directly secured to the main shaft and surrounded by a series of passages for collecting and diverting the gases from one stage of compression to the next. These latter air passages are secured to the internal circumference of the casing of the compressor and may be water cooled by jacket k .

Two or more entrances g arranged on the opposite sides of the main shaft are provided for the entrance of gas or mixture to the rotary compressor.

The rotary compressor a , super-compressor e and turbine c with intervening passage d are all water cooled by jackets k as also the interior of the drum c^4 carrying the rotating blades of the turbine, such water cooling of the drum being effected through the interior of that end of the main shaft which may be bored for the purpose. Also the fixed grille or nozzle plate d^3 may be water cooled by means of water connections to jackets k .

In another embodiment of this invention, as illustrated by Fig. 2, the turbine c may be arranged concentrically around the rotating compressor a , in which case the passages d between the compressor a and the turbine c are arranged at the one end, while the pistons e^1 and sleeve valves e^4 for super-compression are adapted to have a reciprocating movement which is parallel to the main shaft, such movement being obtained through the medium of projecting rollers m and m^1 which are attached to the respective pistons e and slide valves e^4 and which are operated by rotating worm cams m^2 and m^3 which are mounted on the end of the main shaft b .

The operation of the piston e^1 and slide valve e^4 for obtaining the super compression in place of being effected by eccentrics or cams as previously described may be effected by ordinary lift cams, or by cranks.

It will be readily understood that by the shutting off of the mixture by the rotating disk a^1 in the rotary compressor a and the sleeve valve e^4 in the super-compressor, that any possibility of back firing is obviated, and also that by shutting off of the turbine blades before the period of firing any loss of compression is also obviated.

What I claim as my invention and desire to secure by Letters Patent is:—

1. An internal combustion engine comprising a turbine, a compressor located coaxially therewith, and means to increase the compression between said turbine and said compressor, said pressure increasing means also serving to deliver the charge prior to ignition and to seal the ingress of the charge to the explosion space of the turbine.

2. An internal combustion engine comprising a turbine, a compressor located coaxially therewith, and means to increase the compression between said turbine and said compressor, the said compressor being arranged for rotation and being provided with means rotating therewith for shutting off the charge after compression and prior to ignition.

3. A turbine internal combustion engine and rotary compressor having intermediate to the compressor and turbine a super compressor including a piston and a sleeve valve concentric with said piston.

4. In an internal combustion engine, a turbine having a fixed drum and a rotating drum; and also having blades fixed to said drums, rings on said drums, and adjustable screws engaging said rings and causing the same to retain the blades in place.

In witness whereof I have hereunto set my hand in the presence of two witnesses.

GEORGE HENRY HEMINGWAY.
